UNITED STATES PATENT OFFICE

CHARLES B. SHERLOCK, OF WASHINGTON, DISTRICT OF COLUMBIA

DOUBLE IRONING BOARD

Application filed November 20, 1924. Serial No. 751,079.

The object of this invention is to combine a skirt board and a sleeve board by a swivel connection in such manner that the sleeve board may be supported by the skirt board or may 5 support the latter when turned crosswise thereof.

Referring to the drawings forming a part hereof, Fig. 1 is a side elevation with the apparatus resting upon a table, and secured 10 thereto by a hook 4.

Fig. 2 is a side elevation of the same reversed, the skirt board resting directly on the table.

Fig. 3 is a plan view.

15 Referring to the reference numerals, 1 designates the skirt board. 2 is the sleeve board. On one side of the sleeve board is fixed a double footed support 3. This support is attached to the skirt board by means of a bolt 7 passing through the skirt board and extending loosely through the support and threaded into a nut located in a recess in the side of the support next the sleeve board. By this construction the sleeve board may be placed in 20 operative position longitudinally of the skirt board, as in Fig. 2, or crosswise of the skirt board when the latter is to be used, as in Fig. 1.

30 In Fig. 1 the swinging hook 4 is shown fastening the boards to the table on which they rest when in use. A double jointed and footed support 5 is hinged to the board 1 near the free end thereof. This supports the small 35 end of the board 1 when in use, as in Fig. 1. 6 is a hook or catch to hold support 5 out of the way when not in use.

The apparatus may be made of wood, metal, or other suitable material.

40 Such modifications in the structure may be made as fall within the spirit and scope of the claim.

What I claim is:—

45 An ironing board comprising a skirt board and a sleeve board having supporting members for holding said boards parallel to each other, each of said boards forming a support for the other when the other is in use, and a 50 hook on the skirt board for fastening the

structure to a table, one of said supporting members being hinged near one end of the skirt board to be collapsed when the sleeve board is used.
